UNITED STATES PATENT OFFICE

137,138

DESIGN FOR A COMBINED CIGARETTE CASE, MATCH BOX, AND ASH RECEIVER

Carl F. Doeppel, St. Louis, Mo.

Application August 26, 1943, Serial No. 111,004

Term of patent 14 years

To all whom it may concern:

Be it known that I, Carl F. Doeppel, a citizen of the United States, residing in the city of St. Louis, in the State of Missouri, have invented a new, original, and ornamental Design for a Combined Cigarette Case, Match Box, and Ash Receiver, of which the following is a specification, reference being had to the accompanying drawing, forming part thereof.

Figure 1 is a perspective view of a combined cigarette case, match box, and ash receiver, in partially open position, showing my new design; and

The rear and side not shown, are plain.

I claim:

The ornamental design for a combined cigarette case, match box, and ash receiver, as shown and described.

CARL F. DOEPPEL.
